UNITED STATES PATENT OFFICE

1,931,208

BRACKET FOR CONNECTER HEADS

Edward Arthur Robinson, Montreal, Quebec, Canada, assignor to Joseph Robinson, New York, N. Y.

Application May 31, 1930, Serial No. 457,942
Renewed March 9, 1933

3 Claims. (Cl. 285—58)

My invention relates to automatic train pipe connectors with more particular reference to the supporting brackets thereof.

A purpose of my invention is to provide a bracket for a connector of the type indicated that will permit easy separation of the connectors of coupled cars without uncoupling the cars, and that will permit an easy accommodation of the position of the face of the connector to that of the pulling face of the car coupler.

A further purpose is to make a lower portion of a connector bracket of the character indicated longitudinally movable and adjustable with respect to an upper portion, supporting the connector on the lower portion, rigidly fastening the upper portion to the train and providing a T slideway connection between the portions, a rotatable screw having journal support in the upper portion threading the T head of the lower portion.

Further purposes will appear in the specification and in the claims.

I have elected to show one main form only of my invention, selecting a form that is practical and efficient in operation and which well illustrates the principles involved.

Figure 1 is a side elevation of mechanism embodying one form of my invention shown supporting a connector.

Figure 2 is a vertical section taken upon the line 2—2 of Figure 1.

Figure 3 is a fragmentary section taken upon the line 3—3 of Figure 2.

Figure 4 is a longitudinal section through bracket structure shown in Figure 1, the view corresponding to a section taken upon the line 3—3 of Figure 2 to enlarged scale, and showing a portion of my bracket not shown in Figure 3.

Figure 5 is a broken right end elevation of structure shown in Figure 4.

Like numerals refer to like parts in all figures. Describing in illustration and not in limitation and referring to the drawings:—

My invention is directed to means for permitting the mating heads of a train pipe coupling to be separated longitudinally from one another while cars are coupled together, and also for permitting varying the positions of the connector faces to accommodate wear on the knuckle coupler connections between the cars.

I make my bracket 10 that supports one of the mating pipe connectors 11 and 12 of upper and lower portions 13 and 14 respectively.

The upper portion 13 rigidly bolts to the train

55 at 15 and presents a horizontal downwardly di-

rected T slideway 16 to the T head 17 of the lower portions.

The upwardly directed T head 17 of the lower portion fits the downwardly directed horizontal longitudinal slideway of the upper portion and is 60 positioned along the slideway by a rotatable screw member 18 which threads into the head and is journalled at opposite ends in the upper member at 19 and 20, the ends being suitably formed at 21 to receive a wrench. It will be noted that 65 the slideway 16 is formed in the lower side of the upper portion of the bracket and that the slideway and screw member 18 and head 17 of the lower member are enclosed on the top and sides by said upper portion of the bracket. This 70 serves to protect the screw and head 17 and prevents the entrance of snow and ice so that the parts are always in condition to be readily adjusted.

The connectors may be of any suitable type, 75 the lower portion of the bracket being suitably varied to accommodate variant forms of connectors.

In the illustration the connector arms 22 and 23 have forwardly directed hooks 24 that are 80 supported upon and are adapted to rearwardly slide along lateral projections 25 on the lower portion of the bracket.

A rearwardly extending spring 26 is compressed between the forward face 27 of a nut 85 and washer on the rearward end of the hook bolt 28 and the rearwardly presented face of a plate 29 transversely connecting the arms 22 and 23, thereby pressing the connector forwardly.

The lower portion 16 of the bracket is 90 perforated at 30 for easy assembly of the hook end 31 of the bolt 28 which hooks about a crosspiece portion 32 of the bracket near the lower end of the perforation 30.

It will be seen that the bracket and outer end 95 of the spring are tied together by the bolt 28, the connector pressed forward by the spring, positioned rearwardly by its engagement with a mating connector of another car and riding on 100 the side projections 25 of the bracket.

In view of my invention and disclosure variations and modifications to meet individual whim or particular need will doubtless become evident to others skilled in the art, to obtain all or part 105 of the benefits of my invention without copying the structure shown, and I, therefore, claim all such in so far as they fall within the reasonable spirit and scope of my invention.

Having thus described my invention, what I 110

claim as new and desire to secure by Letters Patent is:—

- 5 1. A bracket for a train pipe connector comprising a lower member adapted to make supporting connection with a connector, an upper member adapted to be rigidly fastened to a train, a forwardly and rearwardly horizontal downwardly directed T slideway on the upper member, a head on the lower member fitting the 10 slideway, a forwardly and rearwardly extending screw threading one of the members and journaling in the other adapting the head to be variably slid along the guideway by suitable rotation of the screw.
- 15 2. A bracket for a train pipe connector comprising a lower member adapted to make supporting connection with a connector, an upper member adapted to be rigidly fastened to a train, a forwardly and rearwardly horizontal downwardly directed slideway on the upper member, a T head on the lower member fitting the

slideway, a rearwardly and forwardly extending screw in the slideway threading the head of the lower member, journals for the screw on the upper member across opposite ends of the slideway and a wrench hold extension on the screw. 80

3. A bracket for a train pipe connector comprising an upper member and a lower member, said upper member having a longitudinally arranged portion provided with a slideway on the under side thereof, said slideway being enclosed on the top and sides thereof by said portion, said lower member having a head fitting and slidably arranged in said slideway, a screw extending longitudinally through said slideway and journaled at the ends thereof in said portion, said head on the lower member having a threaded opening through which said screw extends, whereby rotation of the screw will move said head and lower member longitudinally of the slideway. 90
